(57) **CLAIM**

The ornamental design for a pool fill valve, as shown and described.

DESCRIPTION

FIG. 1 is a perspective view of the pool fill valve of the present invention showing my new design with the dotted lines depicting solely environmental structure and forming no part of the claimed design;

FIG. 2 is a top plan view thereof with the dotted lines depicting solely environmental structure and forming no part of the claimed design;

FIG. 3 is a front elevational view thereof with the dotted lines depicting solely environmental structure and forming no part of the claimed design;

FIG. 4 is a bottom plan view thereof with the dotted lines depicting solely environmental structure and forming no part of the claimed design;

FIG. 5 is a rear elevational view thereof with the dotted lines depicting solely environmental structure and forming no part of the claimed design;

FIG. 6 is a left end view thereof with the dotted lines depicting solely environmental structure and forming no part of the claimed design;

FIG. 7 is a right end view thereof with the dotted lines depicting solely environmental structure and forming no part of the claimed design; and,

FIG. 8 is a front elevational view thereof with the dotted lines depicting solely environmental structure and forming no part of the claimed design.

The broken line showing of unclaimed portions form no part of the claimed design.
